US00D499946S

(12) **United States Design Patent** (10) Patent No.: **US D499,946 S**
Stirm (45) Date of Patent: **** Dec. 21, 2004**

(54) **DUST EXTRACTOR**

(75) Inventor: **Michael Stirm**, Oberursel (DE)

(73) Assignee: **Black & Decker Inc.**, Newark, DE
(US)

(**) Term: **14 Years**

(21) Appl. No.: **29/190,751**

(22) Filed: **Sep. 25, 2003**

(30) **Foreign Application Priority Data**

Mar. 28, 2003 (GB) 3011994

(51) LOC (7) Cl. **08-05**

(52) U.S. Cl. **D8/70**

(57) **CLAIM**

The ornamental design for a dust extractor, as shown and described.

DESCRIPTION

FIG. 1 is a left/front perspective view of a dust extractor showing my new design.

FIG. 2 is a left/rear perspective view thereof.

FIG. 3 is a right/front perspective view thereof.

FIG. 4 is a right/rear perspective view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a front elevational view thereof.

FIG. 10 is a rear elevational view thereof.

FIG. 11 is a front perspective view thereof with the telescoping suction tube retracted; and,

FIG. 12 is a left side elevational view thereof with the telescoping suction tube retracted.
